Primary Examiner — Paula Greene(74) *Attorney, Agent, or Firm* — McDermott Will & Emery LLP(57) **CLAIM**

The ornamental design for a headphone, as shown and described.

DESCRIPTION

FIG. 1 is a front view of a headphone showing my new design;

FIG. 2 is a rear view thereof;

FIG. 3 is a top view thereof;

FIG. 4 is a bottom view thereof;

FIG. 5 is a left-side view thereof;

FIG. 6 is a right-side view thereof; and,

FIG. 7 is a perspective view thereof, in which the interior front faces of headphone ear cups are the same as each other.

1 Claim, 7 Drawing Sheets(56)
